UNITED STATES PATENT OFFICE.

WILLIS MITCHELL, OF MALDEN, MASSACHUSETTS, ASSIGNOR OF ONE-HALF TO JOSEPH T. CLARKSON, OF AMESBURY, MASSACHUSETTS.

STEAM-GENERATOR.

SPECIFICATION forming part of Letters Patent No. 767,950, dated August 16, 1904.

Application filed September 17, 1903. Serial No. 173,539. (No model.)

To all whom it may concern:

Be it known that I, WILLIS MITCHELL, a citizen of the United States, residing at Malden, in the county of Middlesex and State of Massachusetts, have invented certain new and useful Improvements in Steam-Generators; and I do hereby declare the following to be a full, clear, and exact description of the invention, such as will enable others skilled in the art to 10 which it appertains to make and use the same.

This invention has for its object to attain the greatest possible efficiency in generating steam within a compact space.

To this end the said invention consists in the 15 combination and construction of parts, substantially as hereinafter more particularly set forth and claimed.

In the accompanying drawings, Figure 1 represents a perspective view of the complete 20 apparatus constituting a steam-generator embodying my invention. Fig. 2 represents a horizontal section of the box and contents, the mixing-chamber, jet-block, and burners being removed. Fig. 3 represents a perspective 25 view of the case, partly broken away to show the contents. Fig. 4 represents a perspective detail view of the mixing-chamber and burners. Fig. 5 represents a similar view of the jet-block and proximate parts. Fig. 6 30 represents a longitudinal sectional view of the latter.

A designates a rectangular flat casing having a series of holes *a* in one end. B designates a water-tube entering the said casing at 35 *b* in one corner and passing out therefrom, as a steam-pipe at *b'*, in another corner diagonally opposite, the said tube being wound between these points of entrance and exit into a series of cylindrical hollow helices *B'*, the 40 bores of which register, respectively, with the said holes *a*. A series of burners *C* pass through these holes into the said hollow helices, becoming cores for the same and discharging flame against the interior faces of 45 said helices from many perforations *c*, distributed over each burner at short intervals in every part of its circumference and length, in order that the water in tube *B* may be heated and converted into steam very rapidly.

as it courses around the said burners. The 50 latter also heat a coiled gasoline-pipe *D*, which extends across the interior of the said case just beyond the ends of the burners and steam-generating helices aforesaid, entering the case *A* at *d* and leaving it at *d'* to connect by a 55 coupling *d'* with a pipe *E*, which discharges into the side passage *f'* of the central bore *f* of a jet-block *F*, having a jet-hole *f''*, controlled by a needle-valve *G*, which passes through a stuffing-box *g*. This jet-block fits 60 against one end of an elongated cylindrical mixing-chamber *H* and discharges the gasoline-vapor into the same, besides permitting air also to enter through holes *h* in said jet-block. The air and inflammable vapor mixing 65 in said chamber flow thence into the said burners, which are rigidly connected to said chamber and extend forward at intervals in parallel lines and at right angles therefrom. The said mixing-chamber is provided with 70 arms or brackets *I* at its ends, arranged to lie along the sides of said case and provided with screw-holes *i* for easy attachment and detachment. A similar bracket *J* in like manner facilitates the attachment and detachment of 75 the jet-block and proximate parts and provides for the support of the same.

In this application I make no claim to the construction of the jet-block valve and stuffing-box and therefore consider an extended 80 description of them unnecessary.

Of course the relative arrangement of the various parts within and outside of the casing, the points of entrance and exit of the tubes, and the form, number, and dimensions 85 of the helices, burners, mixing-chamber, and vapor-generator are capable of considerable modification within the limits of my invention.

The water-tube *B* should be of small diameter and the burners *C* of relative large diameter to get the best results from the steam-generating helices *B'*. The said tube preferably discharges steam into a pressure-tank, whence it passes where and as needed; but of 95 course I do not confine myself to such arrangement and use.

It will be observed that the flame from the

- ends of the burners is directed against the vapor-generator at right angles thereto and that the jets of flame from the holes in the sides of the burners are likewise directed radially 5 against the surrounding steam-tube forming the steam-generating helices in all parts of the length and circumference thereof, also that no part nor material intervenes in either instance.
- 10 Of course the devices aforesaid may be used for generating other vapors and gaseous bodies besides steam.
- Having thus described my invention, what I claim as new, and desire to secure by Letters 15 Patent, is—
1. A steam-generator, consisting solely of a connected series of tubular helices, in combination with a series of laterally-perforated burners each of which is arranged longitudinally in one of the helices and discharges radially directly against the tube composing said helix substantially as set forth.
  2. A series of parallel steam-generating tubular helices and a helical tube arranged across 25 their rear ends for the production of inflammable vapor in combination with a casing, which incloses all of the said parts, but is provided with openings that register with the bores of the said helices, a series of tubular perforated burners C, which are adapted to enter the said helices and discharge against them throughout their length as well as against the said vapor-generating tube, an elongated mixing-chamber H to which the said burners are attached and with which they may be withdrawn from the casing and a tubular connection from the said vapor-generating tube to the said mixing-chamber, supplying vapor to the latter, in order that it may there mix with air 35 and pass thence to the burners substantially as set forth.
  3. A series of steam-generating tubular helices and a generator of inflammable vapor arranged across their rear ends, in combination 45 with a casing, which incloses all of the said parts, but is provided with openings and register with the bores of the said helices, a series of burners which enter the said helices and discharge against them and against the vapor-generator, an elongated mixing-chamber H to which the said burners are connected 50 they being removable thereon, a jet-block discharging into the open end of said mixing-

chamber, a tube connecting said vapor-generator to said jet-block, and a valve coöperating 55 with said jet-block to control the flow of vapor from said generator to the mixing-chamber and burners substantially as set forth.

4. A case inclosing a steam-generator tube, wound into parallel cylindrical helices, burners extending through said helices and discharging from their sides and ends and a generator of inflammable vapor arranged across the ends of the said burners to be heated by all of them, the said generator supplying the 65 said burners through tubular connections for the purpose set forth.

5. In a steam-generator, a helix consisting solely of a tube wound into that form, in combination with a burner constituting a core for 70 the said helix extending for the full length of the latter and discharging radially against the said tube in all parts of the length and circumference of the said helix substantially as set forth.

6. A steam-generator, consisting solely of a connected series of tubular helices, in combination with a series of burners, each of which extends longitudinally through one of the helices and discharges radially directly against 80 the tube thereof at all points of the length and circumference of the said helix substantially as set forth.

7. A steam-generator consisting solely of a pipe wound to form a connected series of steam-generating helices, in combination with a series of burners each extending longitudinally through one of the said helices and a generator of inflammable vapor arranged in front of the discharging ends of the said burners and 85 connected to their inlet ends to supply them with said vapor, the said burners having open discharging ends, directing the flame against the said generator at right angles to the axis thereof and being also provided with lateral 90 perforations which direct radial jets of flame against the tube in all parts of the length and circumference of each helix substantially as set forth.

In testimony whereof I have signed my name 100 to this specification in the presence of two subscribing witnesses.

WILLIS MITCHELL.
